UNITED STATES PATENT OFFICE.

CHARLES FREBORG, OF KANKAKEE, ILLINOIS, ASSIGNOR TO PRICE & TEEPLE PIANO COMPANY, OF CHICAGO, ILLINOIS, A CORPORATION OF ILLINOIS.

MOTOR-MOUNTING FOR PIANO-PLAYERS.

1,267,536.

Specification of Letters Patent. Patented May 28, 1918.

Application filed September 4, 1915. Serial No. 48,973.

To all whom it may concern:

Be it known that I, CHARLES FREBORG, a citizen of the United States, residing at Kankakee, in the county of Kankakee and State of Illinois, have invented certain new and useful Improvements in Motor-Mountings for Piano-Players, of which the following is a specification.

This invention relates to improvements in 10 motor mountings for player pianos, or the like.

It has been found that in the construction and use of player pianos actuated by an electric motor, for example, the vibrations and 15 noises resulting from the operation of the motor are such as to seriously interfere with the satisfactory reproduction of the music. The object of my invention is so to mount the electric motor that it will eliminate this 20 and other disadvantages.

Still another object is to provide a mounting for the operating motor, which consists of flexible members, together with means for varying the tension of such members.

25 Still another object is to provide in connection with a mounting of the kind described above means for deadening the vibrations which might be transmitted from the frame to the motor casing.

30 These and other objects will be set forth and described in the following specification, taken in connection with the accompanying drawings, in which—

Figure 1 is a front elevation of a portion 35 of a player piano showing my invention applied thereto.

Fig. 2 is a vertical section through a portion of the motor casing and frame.

Fig. 3 is a perspective, partially in section, 40 of the motor-supporting means proper.

Fig. 4 is a detail of the motor-supporting frame and cable, and

Fig. 5 is similar to Fig. 2, taken at right angles thereto.

45 Like numerals refer to like elements throughout the drawings, in which—

10 designates generally a player piano, in the base of which I have arranged a casing 11, open at the front, as shown in Fig. 1. 50 In this casing I mount an air-exhausting bellows 12, connected by straps 12^a to an eccentric 13 on the operating shaft 14, the latter being journaled in the bracket 15. A pulley 16 is also secured to the shaft 14. A 55 partition 17 of galvanized metal, or the like,

extends across to the sides of the casing, so as to form the lower portion of the motor compartment 11^a. A pair of cleats 11^b extend from the front to the back of the sides of the casing 11, and are located slightly above the bottom thereof, as shown in Fig. 1. These cleats provide a guide for the motor-supporting means 18, shown in perspective, for example, in Fig. 3. This means comprises a frame formed of the sides 18^a, back 18^b, front 18^c, and cross plate 18^d. The back and sides are secured together, while the front is tongued at 18^e at its ends to slide in grooves 18^f in the sides 18^a. The cross plate extends across between, and is secured to the ends of the sides. Rotatable screws 19 pass through the plate 18^d and engage the front strip 18^c. It will be apparent that the proper rotation of the screws 19 will result in the moving in or out of the front strip 18^c.

75 Cables or rope members 20 extend between the front and back strips 18^c, 18^b, being formed preferably in an endless band, having portions thereof extending through and embedded in such strips, as is clearly shown in Fig. 3. Strips of felt 22 are secured to the back and side strips 18^a, 18^b for a purpose to be hereinafter described. The electric operating motor is indicated by the numeral 25, and rests upon the cables 20 inside 80 the frame, as shown in Figs. 2 and 5, and is secured thereto by a clamping plate 25^a suitably grooved to accommodate the cables 20—see Fig. 5. Suitable strips of felt, or the like, indicated by the numerals 27, are provided at the bottom of the cleats 11^b and the bottom of the casing shown in Fig. 5.

90 When the device is assembled, the frame 18, carrying the motor 25, is slid into position, as shown in Figs. 1, and 2, and the belt 28 is fitted around the driving pulley 25^b and the driven pulley 16. When assembled, operation of the motor will not result in these vibrations being transmitted to the motor casing or piano, since the flexibility 95 of the cable sections eliminates such transmission to a great extent, and the interposition of the strips of felt, 22 and 27, further deadens any such vibrations as might be so transmitted. If the tension of the belt 28 is slack, it may be tightened by loosening screws 19, thus allowing the cable portions to sag more, and, similarly, if the tension be too great, or should the cables have sagged too much, the latter may be 100 105 110

adjusted by utilizing the screws 19 and cross strip 18^a. When it is desired to remove or inspect the motor for any reason, it is only necessary to slip off the belt 28 and draw 5 the frame 18 from the position shown in Fig. 1, while if removal of the motor is desired, it is only necessary to remove the clamping plate 25^a to obtain such result.

It will be apparent from the above that 10 my structure accomplishes all of the advantages set forth in the preamble hereto; and it will also be obvious that it is susceptible of many modifications and changes, and I do not therefore wish to be restricted to the 15 form described and shown beyond the scope of the appended claims.

What I claim is:—

1. In combination with a motor, a supporting member comprising a flexible cross 20 member secured at its ends, said motor being secured to said cross member.

2. In combination with a motor, a supporting member comprising a flexible cross member secured at its ends, said motor being 25 secured to said cross member, and means to vary the flexibility of said cross member.

3. In combination with a motor, a supporting member comprising a flexible cross member secured at its ends, said motor being 30 detachably secured to said cross member.

4. In combination with a motor, a supporting member comprising a frame, and cables extending between the sides of said 35 frame, said motor being secured to said cables.

5. In combination with a motor, a supporting member comprising a frame, cables

extending between the sides of said frame, said motor being secured to said cables, and means to vary the tension in said cables.

6. In combination with a motor, a supporting member comprising a frame, flexible supporting means carried by said frame, said motor being secured to said means, supporting means for said frame and motor, 45 and deadening means located between said frame and supporting means.

7. In combination with a motor, a supporting member comprising a frame, flexible supporting means carried by said frame, 50 said motor being secured to said means, supporting means for said frame and motor, and deadening strips of felt located between said frame and supporting means.

8. In combination with a motor, a supporting means therefor comprising a frame, cables extending between the sides of said frame and attached thereto, and means to vary the relative position of one of said sides to thereby vary the tension in said 60 cables.

9. In combination with a motor, a supporting means therefor comprising a frame, supporting cables extending between the sides of said frame, and means to secure said motor to said cables, said means comprising 65 a detachable clamping plate.

In testimony whereof, I have subscribed my name.

CHARLES FREBORG.
